MULTIPLE SWITCH

Maurice A. Rudd, North Plainfield, N. J., assignor
to Bendix Aviation Corporation, New York,
N. Y., a corporation of Delaware

Application August 29, 1945, Serial No. 613,318.

12 Claims. (Cl. 200—4)

1

This invention relates to switches, and particularly to pluralities of switches mounted for coordination. Inasmuch as one use for such switches is in the control of multi-row radial engines having a plurality of cylinders in each row, occasional reference to such use will be made, but that particular reference is for illustrative purposes only, not in limitation of the invention.

It is an object of this invention to mount a plurality of manually operable switches in a minimum of space for ease of operation and economy of parts and materials.

Another object of the invention is to mount switches performing related functions for alternate or simultaneous operation by a single controlling handle so that their functions may be simply and speedily coordinated, and so that human errors may be substantially eliminated in their manipulation.

Another object of the invention is to assemble a plurality of pairs of switches for operation in pairs and for operation all together, so that the electrical instrumentalities controlled thereby may be affected simultaneously, in pairs or singly as the operator wishes.

Another object is to construct novel, economical, and efficient instrumentalities whereby to accomplish the other objects of the invention, including novel switches, novel operating means, and novel mountings therefor which provide for their efficient operation and for mechanical and electrical shielding.

The above and further objects and novel features of the invention will more fully appear from the following detailed description when the same is read in connection with the accompanying drawings. It is to be expressly understood, however, that the drawings are for the purpose of illustration only and are not intended as a definition of the limits of the invention, reference for this latter purpose being had primarily to the appended claims.

In the drawings, wherein like reference characters refer to like parts throughout the several views,

Fig. 1 is an end view, taken from the left hand end of Fig. 3, of the switch casing, showing the operating levers in various positions;

Fig. 2 is a sectional view on the line 2—2 of Fig. 3 showing the pivoted cam members in various positions. The positions of the cams correspond to the positions of the levers shown in Fig. 1;

Fig. 3 is an enlarged side elevation partly in section of a switch; and

2

Fig. 4 is an end view of the casing taken from the right hand end of Fig. 3.

This invention provides means for coordinating the operation of a plurality of electrical instrumentalities and has wide applications in the electrical industry. A particular example of its use is in connection with internal combustion engines, particularly in connection with those internal combustion engines that have dual ignition for each cylinder. A particular example of use in connection with such engines concerns aircraft engines of radial type having a plurality of cylinders in each radial row. It is not infrequently the case that such cylinders are provided with dual ignition, one spark plug coming in through the left wall of the cylinder and one through the right wall, these spark plugs being called accordingly the left and right plugs, and when they are connected in banks, the left and right plug banks. When connected in banks it is not unusual to find that all the left hand plugs in a particular row of cylinders will be served by one magneto, or by one coil of a magneto, and all the right hand plugs will be served by another magneto or by another magneto coil. It is desirable to test these banks separately in order to determine whether a particular magneto coil has ceased to function or whether particular spark plugs in a row are not working. It is also desirable to ground all the coils of all the magnetos serving the engine, at once. To accomplish all these desirable objectives without impairing the function of the complex ignition system and with simplicity of control is an extremely difficult conception and it was for the accomplishment of this purpose and others of similar nature that this coordinated instrument was invented.

In the drawings the numeral 10 designates a bus bar that is preferably annular, having the general shape of a quadrilateral, in the design of the instrument illustrated in the drawings. The corners of the bus bar shown in Fig. 3 have been replaced by 45 degree diagonal elements 11 in order to reduce the size of the bus bar and to serve as mountings for connections. Upon the bus bar, which is of copper or other conducting metal, are mounted as by means of bolts 12 a plurality of switches indicated generally by the numerals 13, 13', 45, 45'. Inasmuch as these switches may be constructed alike, the description of one will suffice for all of them.

The switch 13 is shown in section in Fig. 3 and it comprises an element 14 and two contacts 15 and 16, contact 15 being normally biased into engagement with the element 14, and contact 16 being normally biased out of engagement.

The contacts 15 and 16 are made of spring material having good conducting properties. A connector 17 makes contact throughout a large portion of its length with the element 14 which it may be connected to by soldering if desired, thus serving not only as a conductor for electrical current, but as a brace for the element 14. The end of the element 14 has bifurcations 14' which may be formed by splitting the end of the element and turning one of the furcations up and the other down as shown. The end of the connector 17 is trifurcated as shown at 17', the outer two furcations being bent upwardly and the intermediate one downwardly to form a guide for a conductor 18 which is attached to the connector 17 by a screw connection 19. This conductor 18 may be considered the source of incoming current for the purpose of description, although it might equally be the carrier for outgoing current, as will be understood by electricians. The contact member 16 is connected at 16' with a conductor 20 which is also connected to like contacts of each switch member mounted on the bus bar. In this way all inner contacts of the switches mounted on the bus bar are connected together and to a connector 21 which is in contact throughout the greater part of its length with a connector 22 which is attached to a conductor 23. The connectors 21, 22 are mounted on the bus bar by screws in a manner similar to the mounting of the switches, except that both connectors are insulated from the bus bar.

The contact 16 of the switch 13, the connector 17, and the element 14 are insulated from the bolts 12 by insulating sleeves 24 and from each other and from the bus bar by insulators 25. The contact 15, which is normally in engagement with one of the furcations 14' of element 14 is separated from the bolts 12 by the sleeves 24 but is electrically connected thereto by a small plate 26 which is of conducting material and makes engagement therewith. It will therefore be apparent that the incoming lead 18 is connected through connector 17, element 14, contact 15, plate 26 and bolt 12 to the bus bar 10. The bus bar is connected to a conductor 27 as by means of a screw 28. The current thus transmitted from lead 18 to bus bar 10 is discharged through the lead 27.

On the end of the contact 15 is an insulator 30 mounted by means of a rivet 31 one end of which is exposed as shown and the other end of which is set within the insulating material so as to be covered thereby. The contact 16 has a stud 32 mounted thereon by means of a rivet 33 which does not make contact with the lower face of the insulator 30 or with the rivet 31. The lower face 32' of the stud 32 is bevelled for a purpose to be hereinafter described. The arrangement of the spring contacts 15 and 16 is preferably such that a small gap is left between them when the contact 15 is engaged with the element 14, but this gap should not be so great that the contact 16 will engage the contact element 14 before the element 15 is disengaged, except in those instances where a temporary simultaneous connection of element 14 with both contacts is desired. When the contact 16 is raised into engagement with the element 14, the contact 15 is thrown out of engagement therewith.

If it be assumed that some electrical instrumentality is operatively connected to lead 18 it will be apparent that this switch may be em-

ployed to connect that instrumentality with one or the other of the electrical conductors 20 and 27. Thus, in the position of the switch shown in the drawing, the instrumentality connected to the lead 18 is connected through the bus bar 10 to the conductor 27. When the contact 15 is out of engagement and contact 16 is in engagement with the element 14 the said instrumentality will be connected through lead 18, connector 17, element 14 and contact 16 to conductor 20—21—22—23.

One use of this invention is in association with a remote control system of operating aircraft engines such as is described in my copending application Serial No. 613,316, filed August 29, 1945, for "Ignition System" (now Patent No. 2,501,410). For that particular use the conductor 18 is connected with a relay switch, the conductor 27 may be connected to the ground line and the conductor 23 to the battery line. Thus in one position of the switch the relay switch will be connected through the bus bar 10 to ground and in the other position of the switch through the lead 20 to a source of power. It will be understood that these connections are illustrative of a use, not a limitation thereto.

This apparatus with its four pairs of switches is desirable and a practical means of accomplishing the desired objectives contemplated by switches I, II, III, IV of said copending application. It will be observed that the control handles of this apparatus are also numbered I, II, III, IV.

If the element 18 is connected in a dual ignition system to the relay switch serving the right hand bank of plugs of a row of cylinders, the switch 13' which is similar in construction to switch 13 may be connected through lead 18' to the relay switch serving the left hand bank of plugs. The novel structure which has already been described cooperates with the novel structure which is about to be described to coordinate the control of both banks of plugs. Similarly, the same coordinated control can be applied to any pair of instrumentalities whose functioning can be coordinated by connection to one or the other of a pair of conductors. The switch 13' being mounted and constructed similarly to switch 13 will operate similarly with respect to the instrumentality to which it is attached. However, the coordination of those switches constitutes another novel conception of this invention.

Mounted upon the bus bar 10 are a number of strong metal elements 40 that are insulated from bar 10, in this instance being four in number, the function of which is to support at one end the base 50 and at the other end the head 70 of a casing. Base 50 has a hollow, annular screw threaded boss 51 through which are passed all the leads that serve the switches. This base member 50 is annular in shape and provided with exterior screw threads 52 for the reception of an internal flange 53 on a protective shell 54. The mounting bars 40 are connected as by screws 41 with the said base member so that the base member and the bus bar are thus firmly united.

At their other ends the supports 40 are similarly connected to the head 70 by screws or bolts 42, the heads of which are covered by a plate 71 held in place by the pins 72 seated in the head 70. Thus, the head, bus bar and base member 50 are firmly united and constitute a frame of

great strength upon which the operating members of the unit may be supported.

The inner face 13 of the head is reduced to provide a shoulder 74 on a flange 75, at the base of which a groove 76, having a conical wall, is formed. This groove serves to seat the square end of the shell 54 so that line contact is provided between the conical wall of the groove and the outer edge of the shell.

Further support in this novel connection is offered by the telescoped lengths of the shell and the part 73 of the head. The internal flange 53 of the shell 54 is heavy and united with the base member 50 to protect the switch mechanism and wiring and to give strong support to the thin part of the metal shell 54.

Member 53 has a raised portion 53' which may be coextensive with the width of member 53 as shown in Fig. 3, or narrower as shown in Fig. 4, and which has therein radial notches or depressions 55. A slotted member 56 having a radial projection 57 is attached to the base member 50 by a screw or bolt 58. This novel locking means enables the base member and the shell to be locked in any selected position with respect to each other.

From the foregoing description and from the showing in the drawings it will be apparent that there has been provided mounting for a gang of switches that are protected against shocks and electrical emanations from outside, and the electrical emanations from which are prevented from passing beyond the metal which preferably constitutes the casing. The novel structure shown in the drawings includes eight such switches, operable in coordinated pairs the elements of each pair being mounted at the corners of the bus bar at 90 degrees to each other. Switch 13', for example, being mounted on the side of the bus bar and switch 13 being mounted on its top. Another pair similarly mounted are shown at 45 and 45'. Each pair is coordinated and operated by novel means mounted in the head. The description of means for operating one pair will suffice for all of them since their construction is preferably similar.

A switch handle IV is attached to a pintle 60 which is mounted for turning movement in the head 70. The pintle has keyed thereto a member 61 which has a plurality of cams, as shown in Fig. 2, which serve as hereinafter described, to operate the two switches 13 and 13'. The stop 62 limits the motion of the member 61. The member 61 is mounted on the pintle 60 by means of a key and slot and a screw 63 so that it is compelled to turn with the pintle. Two spring pressed balls 64, only one of which is shown, are engageable in different combinations with three depressions 65 in one surface of the member 61 to provide four positions of the member 61. These four positions are marked on the plate 71 as "Off," "Right," "Left" and "Both," when the switch is being used for the coordination of the relay switches serving the right and left banks of the spark plugs of a cylinder row. Other notation would be used in conformity with the use to which the switch is being put. There are three cams on the member 61, numbered 66, 67 and 68 which are so located with respect to the cooperating balls 64 and the depressions 65 that they give cooperative positions to levers 77, 78 which are pivotally mounted upon a pin 79 carried by the portion 73 of the head.

The levers 78 and 77 engage the offset ends of the inner contacts 16, 16' of switches 13, 13', re-

spectively. These levers are provided at their ends with projecting rounded contact surfaces for engagement with the ends of the springs and with inwardly directed cams adapted to cooperate with the cams of member 61.

The four positions of the switches are shown in Figs. 1 and 2 by levers I, II, III, and IV. In connection with these figures it should be recalled that front and back views are involved so that 10 moving handle IV clockwise in Fig. 1 moves cam element 61 counter-clockwise in Fig. 2. In the switch position shown for handle I both of the coordinated contacts are thrown outwardly against the tension of the spring contacts. In 15 the position of handle II both the contacts are in their inward position, so that contact is made between the intermediate elements of the switches and the outer contacts thereof. The position of the handle III shows the inner contact of one 20 switch and the outer contact of the other switch engaged. The position of the handle IV shows the engagement of these contacts to be relatively reversed.

Considering the switch assembly to be connected to a relay switch of the stated kind to operate an engine having four rows of cylinders each of which has a left and a right magneto coil serving the left and right banks of plugs, respectively, it will be seen by reference to handle I that both inner contacts have been engaged by throwing the contacts outwardly and that both relays are connected to battery. In the position corresponding to handle II, the relays are both connected through the outer contacts to ground. In 25 the position of handle III the bottom switch member is connected to ground as shown at 45' and the switch 45 connects its relay to battery. In the position of lever IV the relays are connected in reverse order to battery and ground. The magneto coils may be so connected to the 30 relay switches that in the position of the handle "Off," both magneto coils will be grounded by the relays and no firing will occur, in the position "Right" only the right bank will fire, in the position "Left" only the left bank will fire, and in the position "Both" both banks will furnish ignition to the cylinders of their row.

It will be understood that this switch mechanism is to be employed to connect one electrical instrumentality with either of two conductors or alternately to connect either of two electrical instrumentalities alternately to one conductor. For instance, if the lead 21 and the lead 23 were connected to instrumentalities other than battery and ground, they could be connected alternately with the lead 18 through the operation of this switch member. The association of the throw of the switch contacts, the travel of the levers, the placing of the cams on the cam members and the location of the stops and detents are combined elements of novelty which contribute to the production of a unitary, novel and extremely useful result.

It is sometimes desirable and indeed even necessary to provide means by which all switches may be simultaneously thrown in one direction, serving in the case of an ignition circuit such as has just been described to throw all the relays to ground all the magneto coils, as in landing airplanes in an emergency. This novel mechanism comprises a preferably square, plunger-operated cam block 80 having cam faces adapted to engage the bevelled ends 32' of studs 32 simultaneously. This cam block 80 is mounted on the end of a shaft 81 having annular grooves 82, 83 adapted

to cooperate with a spring pressed ball detent 84 mounted in a recess in the head. The shaft 81 is attached to a handle 85 the inner end of which, in the "Off" position, abuts the plate 71 preventing the plunger from being thrust too far into the casing. When it is desired to connect all the circuits simultaneously to ground, or to one conductor, the handle 85 may be pulled, disengaging the groove 82 from the ball detent 84, engaging the cam surfaces of the member 80 with the studs 32 and connecting all the circuits through the inner contacts of the switches with the battery or other suitable source of electrical current. In this position all the switches are simultaneously thrown so as to connect the instrumentalities associated with the switch elements to the battery through the inner switch contacts regardless of levers I, II, III, IV.

There is thus provided an apparatus having switches mounted for coordination in pairs and all together, the mounting of which occupies a minimum of space and of constructional material so that the resulting instrument is light in weight and adapted to use in places where light weight is an advantage.

Another advantage of the invention is in the mounting and coordination of switches to perform related functions by alternate or simultaneous operation, the operation of which is controlled by simple means which tend to eliminate human error.

Other advantages of the invention are recited in the constructional details and assemblage of parts which cooperate for the production of an intricate and unitary result.

Other advantages of the invention are in part apparent and have in part been set forth hereinabove in the specification.

Although only one embodiment of the invention is herein illustrated and described, it is to be expressly understood that the same is not limited thereto. Various changes may be made therein, particularly in the design and arrangement of the parts illustrated without departing from the spirit and scope of the invention, as will now be apparent to those skilled in the art.

What is claimed is:

1. Switch mechanism comprising a switch including a movable contact member and a contact element engageable thereby, means for actuating said member comprising pivoted cam means and a pivoted lever, the free end of which is interposed between and engaged by said cam means and member, said cam means including a cam surface engaged by said lever, whereby movement of said member into and out of contact with said element is effected upon rotation of said cam means, a second movable contact member, a second contact element engageable by the latter, and a second pivoted lever extending between said second contact member and the cam surface of said pivoted cam means, whereby said second contact member is operable by said pivoted cam means, one of said levers making an angle with the other of said levers which includes the pivotal axis of said cam means.

2. Switch mechanism comprising a switch including a movable contact member and a contact element engageable thereby, means for actuating said member comprising pivoted cam means and a pivoted lever, the free end of which is interposed between and engaged by said cam means and member, said cam means including a cam surface engaged by said lever, whereby movement of said member into and out of contact with said

element is effected upon rotation of said cam means, and linearly movable cam means engageable with said movable contact member to operatively actuate the same independently of said pivoted cam means.

3. Switch mechanism as defined in claim 1 wherein the cam surface is formed to actuate said first and second contact members individually and simultaneously to corresponding positions during movement of said pivoted cam means in either direction from one extreme position to the other.

4. Switch mechanism as defined in claim 1 comprising other means for simultaneously actuating said contact members independently of said levers and pivoted cam means

5. Switch mechanism as defined in claim 1 wherein the cam surface is so formed that in four predetermined positions of said pivoted cam means, the first and second movable contact members will assume the following positions relative to the first and second contact elements, respectively: both out of contact, the first in contact and the second out of contact, the second in contact and the first out of contact, and both in contact.

6. Apparatus comprising a plurality of switch mechanisms as defined in claim 1, and linearly movable means for simultaneously moving the movable contact members of all said mechanisms to corresponding positions relative to their respective contact elements independently of the pivoted cam means and the pivoted levers associated therewith.

7. Apparatus including a plurality of switch mechanisms each comprising a switch including a movable contact member, a contact element engageable by said member and means for actuating said member comprising pivoted cam means and a pivoted lever, the free end of which is interposed between and engaged by said cam means and member, said cam means including a cam surface engaged by said lever, whereby movement of said member into and out of contact with said element is effected upon rotation of said cam means, and means for simultaneously moving the movable contact members of all said mechanisms to corresponding positions relative to their respective contact elements independently of the pivoted cam means and the pivoted levers.

8. In an electrical switch assembly, a front panel, an operating handle having a shaft journaled in said panel, a member having a peripheral cam surface and secured to the inner end of said shaft for angular movement therewith, means for yieldably holding said cam member in predetermined angular positions, a lever pivotally mounted on the inner face of said panel with the free end thereof in sliding engagement with said peripheral cam surface, support means secured to said panel and extending rearwardly therefrom, switch means mounted on said support comprising a switch element, a first leaf spring contact at one side of said element and a second leaf spring contact at the other side of said element, said contacts and element being anchored by common means to said support and insulated from one another at the ends thereof remote from said panel, and said first contact being biased to normally engage said element at its free end, insulating spacer means interposed between the free ends of said contacts to prevent simultaneous engagement thereof with said element, the free end of said second spring contact

being biased into engagement with said lever at the free end thereof so as to yieldably press said lever into continuous engagement with said peripheral cam surface, the latter being adapted upon angular movement by said handle to move said second contact into engagement with said element and said first contact out of engagement with said element.

9. An electrical switch assembly as defined in claim 8 wherein said first spring contact is electrically connected to said support by means including said switch mounting means.

10. An electrical switch assembly as defined in claim 8 wherein the free end of said switch element is bifurcated, one furcation thereof being bent in one direction for engagement by said first spring contact and the other furcation being bent in the opposite direction for engagement by said second spring contact.

11. An electrical switch assembly as defined in claim 8 comprising a second lever pivotally mounted on the same axis as said first-named lever and engaging said peripheral cam surface, one of said levers making an angle with the other which includes the pivotal axis of said cam member, and a second switch means like said first-named switch means adapted to cooperate with said second lever in the same manner that said first-named lever and switch means cooperate, said cam surface being so formed as to

5

10

15

25

30

hold either one, both or neither of said second leaf spring contacts in engagement with its respective switch element depending upon the angular position of said cam member.

12. An electrical switch assembly as defined in claim 11 comprising a plurality of pairs of switches and operating means for each said pair as defined in said claim 11, and linearly movable means slidably mounted in said front panel for simultaneously moving all of said second spring contacts into engagement with their respective switch elements.
